(57) **CLAIM**

We claim the ornamental design for a hub for medical fiber connector devices, as shown and described.

DESCRIPTION

FIG. 1 is a perspective view of a hub for medical fiber connector devices, showing our new design;

FIG. 2 is a front view thereof;

FIG. 3 is a back view thereof;

FIG. 4 is a top view thereof;

FIG. 5 is a side view thereof, the opposite side being a mirror image thereof; and,

FIG. 6 is a bottom view thereof.

In the drawings, the broken lines represent portions of the article which form no part of the claimed design.
